UNITED STATES PATENT OFFICE.

HOWARD S. ROCKWOOD, OF PROVIDENCE, RHODE ISLAND, ASSIGNOR TO
THE HOLMES MANUFACTURING COMPANY, OF SAME PLACE.

BUTTON-FASTENER.

SPECIFICATION forming part of Letters Patent No. 449,648, dated March 31, 1891.

Application filed October 14, 1890. Serial No. 368,096. (No model.)

To all whom it may concern:

Be it known that I, HOWARD S. ROCKWOOD, a citizen of the United States, and a resident of Providence, in the State of Rhode Island, have 5 invented a certain new and useful Improvement in Button-Fasteners, of which the following is a specification.

My invention relates to fasteners for that class of buttons which are provided with eyes 10 which are passed through slots or openings previously formed in the fabric to which the button is to be secured, and more particularly to that class of button-fasteners which are generally known as "eyelet button-fasteners," to 15 distinguish them from so-called "staple button-fasteners;" and my invention consists in an eyelet button-fastener made in disk form, which can be readily attached to or removed 20 from the eye of the button, as will be clearly understood by referring to the drawings, in which—

Figure 1 is a plan view of my improved fastener. Fig. 2 represents a section of the same, taken on the line $x-x$, Fig. 1, showing 25 the button in proper position. Fig. 3 is a bottom view of the fastener and button combined. Fig. 4 is a section taken on line $y-y$, Fig. 1.

In eyelet button-fasteners as heretofore 30 made the tongue which passes through the eye of the button is liable to be bent by constant strain out of its original and proper form, so as to allow its free end to project beyond the convex surface of the disk, thus 35 causing considerable annoyance to the wearer from its frequent catching into the meshes of the stocking, which results in tearing the same or bending the tongue so that it will press into the flesh of the foot. It is the object 40 of my invention to obviate these difficulties, and, furthermore, to so form the tongue that it is practically impossible to disarrange the tongue so as to prevent the fastener from being readily removed from the button when 45 desired.

In the accompanying drawings, A represents a slightly-hollowed disk provided with the cut-out tongue a , which is made in curved form, the end e of which is turned inward, so as to enter the shallow cavity of the said disk. 50 Near the center of the disk, as at b , the tongue may be arched to an extent preferably of about the diameter of the wire of which the button-eye is made, and the disk itself is so cut out as to leave openings c on both sides 55 of the tongue a , the edges of the said openings c being turned inward, as shown in Fig. 4. It will thus be seen that there will be no angular edges or projections exposed to contact with the stocking, and that therefore it 60 will be impossible for the disk to get caught in the fabric or to injure the same.

Whenever it is desired to fasten a button, the inwardly-turned end of the tongue is passed through the eye of the button and the 65 disk is turned so as to cause the tongue to slide along in the eye until the latter reaches the arched portion of the tongue near the center of the disk.

The tongue a is so cut from the disk that 70 it will start directly forward from its attaching-point, then curve to one side and backward, so that the end of the tongue will not be liable to project injuriously from the disk when in use. 75

I claim as my invention—

A button-fastener consisting of a concave disk provided with an integral tongue cut centrally therefrom, the said tongue extending forward from its connecting-point, then 80 curving to one side and backward, and terminating in an upturned end, substantially as described.

HOWARD S. ROCKWOOD.
